BIAS TUBING

Julius Katz, Bronx, and Frank P. Majeros, Brooklyn, N. Y., assignors to Superba Manufacturing Co., Inc., New York, N. Y., a corporation of New York

Application January 18, 1945, Serial No. 573,364

2 Claims. (Cl. 112—63)

1

This invention relates to the method of forming cloth into bias seamed tubing in which the bias seam does not run helically throughout the length of the tubing, but is disposed diagonally of the cloth and is made up of separate spaced spiral convolutions.

Helically bias seamed tubing is being used to a limited extent in the bag industry, but the complicated methods employed to produce the article have considerably hindered wider use in this field. It is the object of the present invention to provide a cloth tubing in which the threads are diagonally placed with respect to each other and the bias cutting of the threads is controlled so that the angle or degree of bias cut will predetermine the position of the threads. Bias seam tubing possesses a resiliency, as does all bias cut cloth materials, and according to the present invention the degree of resiliency is predetermined by the angle or degree that the threads are disposed. In using bias tubing for bagging purposes, it is necessary to control the stretch of the bag and the present method accurately exercises such control.

The present invention has the further advantage of producing tubular bagging material, of any size, efficiently, quickly and inexpensively. This is accomplished by superposing strips upon each other or by dividing the bias strip longitudinally into as many sections as desirable and then by seaming the divided sections together along their longitudinal sides so that a bag tubing is produced of the desired diameter.

The objects of this invention are accomplished by means of the several steps in the method hereinafter described, set forth in the appended claims, and illustratively exemplified in the accompanying drawings, in which:

Figures 1 and 2 are elevational views showing the progress of a strip of woven cloth material, from a flat state into a tubing which is then rotated spirally into the path of a blade and finally severed into a bias strip;

Figure 3 illustrates the step of forming the bias strip into bias tubing;

Figure 4 is a side view of the bias tubing showing the disposition of the spiral seam with respect to the longitudinal side seam;

Figure 5 is a substantially transverse sectional view of bias tubing taken on lines 5—5 of Figure 3;

Figure 6 illustratively exemplifies the step of converting the bias tubing into strip wherein the direction of the threads of the original material

2

of Figure 1 are reversed to produce a strip of cross cut material;

Figure 7 is an elevational view of a tubing material of knitted, woven or braided construction in which no seam is present and from which a bias strip is being cut in the manner of Figure 2;

Figure 8 is an elevational view of a bias strip of Figure 7 being formed into a bias tubing by seaming together the longitudinal side edges of the bias strip, in the manner of Figure 1;

Figure 9 is an elevational view of a tubing material which is formed by using two or more bias strips of the material and attaching them together along their longitudinal side edges to form a tubing of any diameter required for bagging.

Figure 10 is a plan view of a strip of bias material embodying attached diamond shaped bias pieces.

Referring to the drawings, and especially Figures 1 and 2, we illustrate a straight length of cloth or similar material which is folded longitudinally of itself and its side edges stitched together to form a tube, the tube being moved along in a spiral direction into the path of a cutting element which severs the tube into a continuous bias strip. This is the well known method of producing bias strip material.

The next move in the present method, see Figures 3 to 5, involves the step of tubing the bias material by bringing together the longitudinal side edges of the strip and stitching or otherwise seaming them to form a bias seamed tubing illustratively exemplified in Figures 3 and 4; Figure 4 being an elevational view of the tubing and illustrating the arrangement of longitudinal and interrupted spiral seams. The longitudinal stitching forming the seam intersects the crossed bias threads of the material forming an angle which is either substantially less than or substantially greater than a right angle.

In the drawings, 10 denotes the straight cloth strip and 11 the seam formed by joining together its opposite longitudinal side edges. The tubing 12 thus formed is fed spirally over and along a mandrel 13 by means of feed rollers 14, the material being severed into a bias strip 15 by means of a cutting element 16 arranged on the mandrel in the path of the spirally fed tubing. The bias strip 15 is a length of cloth comprising bias sections 17 joined together by the diagonal seam 18, which is a section of the longitudinal seam 11.

The bias strip 15, see Figures 3 and 4, is then joined along its longitudinal side edges by a seam 19 to form a so-called bias tubing 20. In accordance with the present method, each diagonal seam

18, when the bias tubing is formed, describes a complete convolution running helically from the longitudinal seam 19, the ends of each seam 18 beginning and ending in the seam 19 and being spaced longitudinally of each other and from the ends of adjacent helically or diagonally disposed seams 18. The product thus produced is a length of bias tubing having the longitudinal seam 19 running along one side and spaced diagonally disposed seams running helically about the tubing, the ends of each diagonal seam being spaced from each other along the longitudinal seam and from the ends of adjacent diagonal seams. The bias seamed tubing is finally cut into desired lengths and the open ends closed to form bags.

It may become necessary to utilize the bias seamed tubing for other purposes, i. e., for producing a strip of material in which the direction of the threads have been reversed. In other words, the threads of the cloth which originally were longitudinal are arranged so as to run transversely of the strip, while the originally transverse threads will be reversed and run longitudinally of the strip. The step in the method of producing such so-called cross cut material is illustratively exemplified in Figure 6, which shows the bias seamed tubing 20 being fed spirally over a mandrel 21 and into the path of a cutter 22, which is disposed at an angle to the longitudinal axis of the tubing and at an angle to the diagonal seams 18 and longitudinal seam 19. In this cross cut the cutter 22 severs the tubing along the threads which originally ran transversely of the cloth so that the strip 23 thus produced would appear approximately as shown in Figure 6.

In Figures 7 and 8, we have illustrated the steps required in the present method of producing bias tubing from tubular knitted, woven or braided material, i. e., straight seamless tubing designated 23'. The first step is to spirally rotate the tubing 23' over a mandrel 24 or other support so as to enable the cutter 25 to sever the material into a continuous seamless bias strip 26. The final step is to form the bias strip 26 into a bias tubing 27 by bringing together the longitudinal side edges of the bias strip and attaching the same by a row of stitching or other method of forming a seam 28. The longitudinal stitching forming the seam intersects the crossed bias threads of the material forming an angle 50 which is either substantially less than or substantially greater than a right angle. As a result of this method, we have a bagging material which has only the longitudinal side seam 28 and which is provided with all of the desired resiliency of the bagging material of Figures 3 to 5.

Referring now to Figure 9, we show at least two separate bias strips 15 attached together along their longitudinal side edges by means of seams 29 to form bias tubing 30. The purpose 5 of this particular arrangement is to create tubular bagging 30 of substantially any width or diameter depending upon the widths of the bias strips used in the construction. While the bias strips illustrated are those produced by the method of Figure 2, the strips may just as well be those of the method of Figure 7.

Referring to Figure 10, the strip of bias material comprises diamond shaped bias pieces 31 of material attached together by seams 32, the 15 tubing being formed by bringing together the longitudinal side edges and seaming the same longitudinally.

Having described the present invention and the manner in which the several steps are carried out, what is claimed is:

20 1. A method of manufacturing tubular bias bagging material from unbiased tubular textile material which comprises the steps of cutting said tubular material along the convolutions of a continuous helical line to obtain cut-edged bias material and thereafter joining the said bias material adjacent the cut edges to form tubular bias bagging material.

25 2. A tubular bagging material comprising bias cloth seamed along the adjacent longitudinal edges thereof to form a tube, the seaming intersecting the crossed bias threads of the material and forming an angle thereto which is either substantially less than or substantially greater than 35 a right angle.
